OIL WELL PUMP

Wilfred S. Crake, Houston, Tex., assignor to Shell Development Company, San Francisco, Calif., a corporation of Delaware

Application January 11, 1949, Serial No. 70,324

5 Claims. (Cl. 103—219)

1

This invention relates to the art of producing hydrocarbon materials from underground formations, and pertains more particularly to an improved oil well pump adapted to be actuated by the reciprocation of the tubing string.

Conventional oil well pumps are usually operated by reciprocating a string of sucker rods within a tubing or flow string which is, in turn, run within the well casing. The pump is installed at the lower end of the tubing string and is supported thereby, the pump plunger being reciprocated through said sucker rod string by suitable prime-mover means at the surface. The sucker rod string is furthermore used, in well known fashion, to install and to withdraw the plunger and travelling valves of the pump.

A modification of this system is to be found in so-called casing pumps, wherein the pump is anchored directly in the well casing at the desired depth, and the tubing string is eliminated, the sucker rods reciprocating directly within the casing. The casing pump depends for its operativeness on the feature of packing off the casing above the pump, whereby the casing itself serves as a tubing string. This type of pump is, however, not suitable for wells having low fluid levels and producing large or even normal quantities of formation gas, because the gas can be produced to the surface only through the pump, and causes frequent failures of the pump due to gas lock.

In my previous Patent No. 2,383,934 on an "Oil Well Pump," there is disclosed an oil well pump of the reciprocating-plunger type adapted to be reciprocated by a tubing string, said pump comprising a valved plunger affixed to the lower end of said tubing string, a pump barrel slidably fitting around said plunger, and upper and lower anchoring means outwardly carried by the pump barrel to anchor the pump barrel against upward and downward motion, respectively, in the well. The upper anchoring means is adapted to be set in the well in response to an axial movement of the tubing string with respect to the pump barrel after the pump barrel has been anchored in the well by the lower anchoring means.

While the aforesaid apparatus is extremely useful, it has been found that during operation of said pump the lower anchoring means or hold-down mechanism was often subject to accidental tripping, thus necessitating the reanchoring of the pump within the well.

Additionally, the above-mentioned method of anchoring pumps in a well necessitates the manipulation of the entire tubing string, either

2

axially or rotationally, in order to actuate the anchoring means carried by said pumps.

It is, therefore, an object of the present invention to provide a pump system wherein the tubing string is used during operation, as actuating means for supplying motive power to the pump, as conduit means for conveying the liquid output of the pump to the surface, and as conduit means for supplying an actuating fluid for the hydraulically-operated anchoring means carried by said pump.

It is also an object of this invention to provide an improved and simplified pump installation wherein the sucker rod is eliminated and the pump, carrying hydraulically-operated anchoring means, is installed, reciprocated during operation, and removed solely by means of the tubing string.

Another object of the present invention is to provide a pump, adapted to be actuated by a tubing string, including a single hydraulically-operated anchoring device carried by said pump for fixedly anchoring said pump in a well against both upward and downward motion.

These and other objects of this invention will be understood from the following description taken with reference to the attached drawing wherein:

Figures 1 and 1a are longitudinal views, partly in cross section, showing the present pump anchored in place within a well casing.

Figure 2 is a cross-sectional view of the lower end of the pump plunger shown in Figure 1a, said view being taken at 90° thereto.

Figure 3 is a cross-sectional view of the tubing drain of Figure 1 in an open position.

Referring to Figure 1 of the drawing, the present pump is shown as being positioned in a well having a casing 11 and a casinghead 9, provided with suitable conduit connections 8 for the removal of gases entering the casing in the well.

The pump is attached to the end of a tubing string 5 which passes into the casing through a suitable lubricator device 7. The tubing 5 serves for imparting a reciprocating motion to the pump, as will be described hereinbelow, and is for this purpose connected at 3 to a cable or similar means 2 leading to prime mover means such as a walking beam, not shown. The tubing 5 also serves as a flow or eduction tube for oil being pumped, and is connected, through a swivel head 4, to an output conduit 1.

Secured to the bottom of the tubing string 5 by a coupling 12 is a tubing drain 13 of a suitable type. In this embodiment the tubing drain 13, shown in Figures 1 and 3, may comprise two short

concentric tubular members 14 and 15 respectively. The inner tubular member 14 is mounted for limited axial and rotational motion within the outer tubular member 15, said axial movement being limited by an annular inner flange 16 formed on the inner surface of the outer member 15 and an annular outer flange 17 carried by the inner member 14.

The outer member 15 has formed therein a J-slot 18 adapted to receive a pin 19 carried on the outer surface of the inner member 14. One or more fluid outlet ports 20 formed in the walls of said outer member 15 permit fluid to drain out of the tubing string 5 when the drain 13 is in its open position, as shown in Figure 3. When the pin 19 engages the slot 18, as shown in Figure 1, the tubing drain is in its closed position with the annular flange 17 closing the fluid outlet ports 20 and the tapered lower surface 21 of said flange being seated on a shoulder 22 formed within said outer tubular member 15. The lower end 23 of the inner tubular member 14 extends below the flange 17 and carries a sealing ring 24, of any suitable packing material, which forms a fluidtight seal with the inner wall of the outer tubular member 15 when the tubing drain is closed or in the pumping position. During pumping operations, fluid passes upward through coaxial bores 25 and 26 of the tubing drain 13.

Secured by screw threads 27 to the outer and lower tubular member 15 of the tubing drain 13 and in communication with the bore 26 thereof is a section of tubing 28 forming the upper polished plunger that extends through the upper barrel 29 into the enlarged lower pump barrel 30 to form an annular chamber 31 between said tubing 28 and barrel 29 and a second annular chamber 32 between said tubing 28 and barrel 30. Attached to the lower end of the tubing 28, as shown at 33 is a hollow plunger 57, having an outside diameter larger than that of the tubing 28 and adapted for a sliding fit within the barrel 30. The plunger 57 is provided with a passage or fluid port 65, opening to the space within the lower pump barrel 30 below the plunger and forming a valve seat for an upwardly opening ball valve 61, held in place by a baffle plate 59. The plunger also has ports 55 in communication with the space within the pump barrel above the plunger.

The tubing 28 is provided, at a suitable distance above the plunger, with lateral ports 44 in communication with the chamber 32. Mounted within the tubing 28 above these ports is a valve structure comprising a valve seat 40, an upwardly opening ball valve 38, a baffle pin 36, and an orifice 42.

The lower pump barrel 30 is closed near the lower end by a transverse member or plate 67, having therethrough an orifice or fluid port 68 in register with a downwardly extending tube 69 depending from said plate. Ports 71 are formed in the walls of the pump barrel above the lower end of the tube 69 to permit the inflow of fluid from the well, and the pump barrel or housing 30 is closed at its lower end by a bull plug 72, the arrangement 67-69-71 thus forming in effect a gas anchor for the pump. A key 62, integrally formed on or fixedly secured to the bottom of the plunger 57, is adapted to engage a keyway 63 in the plate 67.

In this embodiment the upper pump barrel is divided into two sections 29 and 29A that carry between them suitable hydraulically-operated pump and anchoring means for positioning said

pump in the well casing 11 at any predetermined depth.

The pump anchoring means comprises a tubular mandrel 33 having internally threaded end portions 34 and 35 whereby it is connected to the upper pump barrel sections 29 and 29A thus forming a portion of the upper barrel. A series of ports 37 extend laterally through the mandrel 33 and provide piston chambers for pistons 39 that are affixed to or integrally formed with a plurality of slip segments 41. The inner and outer surfaces of the slips 41 are curved so that said inner surfaces conform to the outer surface of the mandrel 33, and said outer surfaces conform substantially to the inner surface of the casing 11. The outer surfaces 45 of the slips 41 are serrated or toothed, preferably in a V-shape to prevent slippage of the pump in either direction. The slips 41 are mounted for limited lateral or radial movement and are actuated by fluid pressure acting against the pistons 39. The pistons 39 may be equipped with suitable piston rings or O-ring seals 43 to form a fluidtight seal between said pistons 41 and the wall of the piston chambers. The annular chamber 31 formed between the tubing member 28 and the mandrel 33 is in communication with the inside of said tubing member 28 through port means or apertures 47 in the wall of said tubing member 28.

The upper barrel 29 and 29A is swaged at its upper and lower ends 73 and 74, respectively, in substantially fluidtight contact with the tubing member 28. Preferably, however, one or more seal cups 75 and 76 are carried on the tubing member 28 on either side of the apertures 47 therethrough thus forming a pressure chamber 31 between said tubing member 28, mandrel 33 and seal cups 75 and 76. If desired, a centralizing spring 77 may be secured to the upper barrel 29 in any suitable manner to position the barrel centrally in the casing 11. Additionally a rubber casing protector 78 may be affixed to the tubing string 5 to prevent the tubing drain 13 from contacting the casing 11 while the pump is being reciprocated.

In operations, the above-described apparatus is lowered on the end of a tubing string 5 to a predetermined level in a well. With the pump at the desired depth the tubing string 5 is filled, from its open end at the surface, with a quantity of liquid sufficient to actuate the pump anchoring means. The tubing drain 13 is, of course, in a closed position, as shown in Figure 1, when the pump is being positioned in the well. Any suitable fluid may be run into the tubing string 5 to actuate the anchoring means. Preferably, well fluid or a fluid having substantially the same composition of well fluid is employed.

The fluid added to the section of tubing 28 flows out the tubing apertures 47 filling chamber 31 between said tubing 28 and mandrel 33. Thus, any fluid in said tubing 5 and 28 becomes the pressure fluid for actuating the pistons 39 of said hydraulic anchoring means. When a sufficient length, say 1,000 feet, of the tubing has been filled with fluid, the piston 39 and attached slips 41 move laterally until the slips 41 engage the walls of the casing 11, as shown in Figure 1.

The pump is now installed and anchored within the casing 11 against either downward or upward motion and is ready for reciprocation of the tubing 5. During pumping, the lengths of the stroke of the plunger 57 and tubing 28 are selected so that the plunger 57 and the tubing

drain 13 do not strike the plate 67 and upper barrel 29 at the end of the down stroke, and plunger 57 does not strike the top of the lower pump barrel 30 at the end of the upstroke of the pump. Also, the seal cups 75 and 76 are spaced so that they do not strike the swaged ends 73 and 74 of the upper pump barrel 29 and 29A.

As the pump plunger 57 is reciprocated within the pump barrel 30 by means of tubing string 5 and suspending elements 2 and 3 from a prime mover element on the surface such as a walking beam, not shown, the flow of well liquid proceeds to the surface as follows:

During the downward stroke, valve 38 is closed by the column of fluid in the tubing 5 and the well fluid enters the lower pump barrel 30 through ports 71 and 69, passes into the plunger 57 as valve 61 is open and thence into chamber 32 through ports 55 due to the vacuum created in chamber 32 above the plunger 57 by the downward displacement of said plunger. On the upward stroke, the valve 61 is closed and the fluid displaced from the chamber 32 by the rising plunger is forced through ports 44, past opened valve 38, upwards through the tubing 28, tubing drain 13 and into tubing string 5. Throughout the pumping operation the pressure fluid in the tubing 5 is preferably in communication with the pressure chamber 31 through apertures 47.

The tubing 28 and plunger 57 are normally of sufficient length so that an additional lowering of the plunger 57 below the lowest point in its normal downstroke permits it to contact the plate 67. When it is desired to raise the pump out of the well the tubing string 5 and tubing 28 are lowered until the plunger touches the plate 67. The tubing 5 is then rotated slightly from the surface until the key 62 on the bottom of the plunger 57 engages the keyway 63 in plate 67. Thus, plunger 57, tubing 28 and the outer tubular member 15 fixedly attached to said tubing 28 are restricted from further rotary motion. Continued rotation of the tubing string 5 in a clockwise direction causes the pin 19 to move out of the J-slot of the tubing drain 13, whereby the tubing string 5 and inner tubular member 14 attached to said tubing string may be raised. As shown in Figure 3, on raising the inner tubular member 14 of the tubing drain the flange 17 normally closing the drain ports 20 is raised opening said ports 20 thus permitting the liquid to drain from the tubing string 5 out the ports 20 and into the well again. With the pressure fluid drained from the tubing 5, pressure is removed from the pressure chamber 31 of the pump anchoring means allowing the slip segments 41 to be forced back against the mandrel 33 by contact with the casing 11 when the pump is removed from the well.

The construction of the tubing pump of the present invention has been found to be particularly advantageous in that only a single hydraulically operated anchoring means need be employed to securely anchor the pump in the well casing against either upward or downward movement. The pump also may be set and securely anchored without manipulation of the tubing string.

I claim as my invention:

1. A well pump adapted to be positioned within the casing of a well at the end of a reciprocating string of tubing, said pump comprising a valved plunger affixed to the lower end of said tubing for reciprocation therewith, a pump barrel slidably surrounding said plunger and the lower portion of said tubing, and hydraulically

operated slip means outwardly mounted on said barrel, said slip means comprising piston means responsive to the hydraulic pressure of a fluid standing in the tubing for engaging said slip means with said casing to anchor said pump therein.

2. A pump installation for well producing a fluid through a string of casing, comprising a string of tubing within said string of casing, 10 prime mover means affixed to the upper end of said string of tubing for reciprocating said string of tubing, a valved plunger affixed to the lower end of said string of tubing for reciprocation therewith, a pump barrel slidably surrounding 15 said plunger and the lower portion of said tubing, and hydraulically operated slip means outwardly mounted on said barrel, said slip means comprising piston means responsive to the hydraulic pressure of a fluid standing in the tubing for engaging said slip means with said casing to anchor 20 said pump therein.

3. A well pump adapted to be positioned within the casing of a well at the end of a reciprocating string of tubing, said pump comprising a valved 25 plunger affixed to the lower end of said tubing for reciprocation therewith, a pump barrel slidably surrounding said plunger and the lower portion of said tubing, hydraulically operated slip means outwardly mounted on said barrel, said 30 slip means comprising piston means affixed to said slip means responsive to the hydraulic pressure of a fluid standing in the tubing for engaging said slip means with said casing to anchor said pump therein, and a normally closed tubular 35 drain element connected into the tubing string above said pump surface to drain said tubing of fluid, whereby said slip means are released from engagement with the casing.

4. A well pump adapted to be positioned within 40 the casing of a well at the end of a reciprocating string of tubing, said pump comprising, in combination, a valved plunger affixed to the lower end of said tubing for limited stroke reciprocation therewith, a pump barrel slidably surrounding 45 said plunger, said pump barrel having an upper and a lower fluidtight section, said plunger being enclosed within said lower fluidtight section, hydraulically operated slip means outwardly mounted on said upper pump barrel section for limited lateral movement, said slip means comprising piston means affixed to said slip means and carried by said upper pump barrel section, port means through the wall of said tubing in 50 communication between the inside of said tubing and the space adjacent the piston means, said piston means being responsive to the hydraulic pressure of a fluid standing in the tubing for engaging said slip means with said casing to anchor said pump therein, a normally closed drain element connected into the tubing string above said 55 pump, and locking means carried by said drain element and operable by manipulation of the tubing string from the surface to open said drain element, whereby said slip means are released from engagement with the casing by the draining of the fluid in the tubing.

5. A well pump adapted to be positioned within 60 the casing of a well at the end of a reciprocating string of tubing, said pump comprising, in combination, a valved plunger affixed to the lower end of said tubing for limited stroke reciprocation therewith, a pump barrel slidably surrounding said plunger, said pump barrel having an upper and a lower fluidtight section, said plunger being 65 enclosed within said lower fluidtight section, slip

means outwardly mounted on said upper pump barrel section for limited lateral movement, aperture means through the wall of said tubing in communication between the inside of said tubing and the space inside the upper section of said pump barrel, ports through the wall of said upper pump barrel section in register with the inner faces of said slip means, piston means affixed to said slip means mounted for lateral movement in said port means, said piston means being responsive to the hydraulic pressure of a fluid standing in the tubing for engaging said slip means with said casing to anchor said pump therein, and a normally closed tubular drain element connected into the tubing string above said

10

15

pump and operable from the surface to drain said tubing of fluid whereby said slip means are released from engagement with the casing.
